L. F. PERKETT AND E. C. MADARY,
REFRIGERATOR CONSTRUCTION.
APPLICATION FILED MAR. 8, 1915.

1,358,781.

Patented Nov. 16, 1920.

UNITED STATES PATENT OFFICE.

LOUIS F. PERKETT AND EDWARD C. MADARY, OF TRAVERSE CITY, MICHIGAN,
ASSIGNORS, BY MESNE ASSIGNMENTS, TO JOHNSON-RANDALL COMPANY,
OF TRAVERSE CITY, MICHIGAN, A CORPORATION OF MICHIGAN.

REFRIGERATOR CONSTRUCTION.

1,358,781.

Specification of Letters Patent. Patented Nov. 16, 1920.

Application filed March 8, 1915. Serial No. 12,826.

To all whom it may concern:

Be it known that we, LOUIS F. PERKETT and EDWARD C. MADARY, citizens of the United States, residing at Traverse City, in the county of Grand Traverse and State of Michigan, have invented certain new and useful Improvements in Refrigerator Construction, of which the following is a specification.

10 This invention relates to improvements in refrigerator construction and one of the objects of the same is to provide an improved device of this character which will be constructed of fiber board, whereby the weight 15 of the structure will be materially reduced and at the same time will result in a moisture and heat proof structure and the cost of manufacture will be materially reduced.

To the attainment of these ends and the 20 accomplishment of other new and useful objects as will appear, the invention consists in the features of novelty in substantially the construction, combination and arrangement of the several parts hereinafter more 25 fully described and claimed and shown in the accompanying drawing illustrating the invention, and in which,

Figure 1 is a perspective view of an improved refrigerator of this character, constructed in accordance with the principles of this invention.

Fig. 2 is a transverse horizontal sectional view of Fig. 1.

Referring more particularly to the drawing, the numeral 10 designates corner uprights which may be constructed of any suitable material such as wood, and secured to these uprights to form the back and side walls 11, 12 are sheets of wood or paper 35 fiber board, commonly known as straw board and are fastened to the uprights in any suitable manner, the edges of adjacent boards being secured together in any suitable manner such as by means of angle irons 40 13. The top of the structure is formed by the wall 14 which is also constructed of fiber board and angle irons 15 are secured over the edges of the top and the adjacent side and end walls.

45 The bottom of the structure is formed in any suitable manner.

The front 16 is constructed of any suitable material such as wood and this front is pro-

vided with door openings closed by suitable doors 17, 18, and each of the doors is preferably provided with a panel 19 constructed of fiber board and the doors are insulated by means of suitable insulation 20, such as cork or the like and which insulation is arranged between the spaced walls 21, also constructed of fiber board.

The doors engage or abut against the jambs 22, secured in position in any suitable manner. Arranged within the structure thus formed and preferably secured to the inner faces of the uprights 10, are walls 23, which are also constructed of fiber board, and these walls are secured in position in any suitable manner. Additional uprights 24 are arranged between the walls 12, 23, preferably adjacent the uprights 10 and a similar wall 25, constructed of fiber board is secured to the outer faces of these uprights 24 so as to form dead air spaces 26 between the outer walls 11 and the adjacent walls 25 of the structure. Between the walls 23 and 25 is arranged suitable insulating material, such as cork insulation 27, whereby the interior of the structure will be insulated against heat.

The inner faces of the walls 23 are coated with any suitable material to prepare the faces for a coating 28 of enamel or finishing material.

With this improved structure it will be manifest that an extremely light, simple, durable and cheap construction will be produced, and a structure which will be thoroughly insulated against heat at a cost materially less than the cost of a similar structure made of wood or other material.

What is claimed as new is:

1. A refrigerator having outer walls constructed of fiber board, corner uprights to which the fiber is secured, inner walls constructed of fiber board, said inner walls secured to the uprights and spaced from the outer walls, additional uprights within the spaces and adjacent the first said uprights, said additional uprights extending only partially across the respective spaces, partitions constructed of fiber board, arranged in the spaces and secured to the said additional uprights, said partitions co-operating with the inner walls of the refrigerator to form insulation spaces, and insulating material.

in said insulation spaces, the spaces between the partitions and the respective adjacent outer walls forming dead air spaces.

2. A refrigerator having outer walls constructed of fiber board, corner uprights to which the fiber is secured, inner walls constructed of fiber board, said inner walls secured to the uprights and spaced from the outer walls, additional uprights within the spaces and adjacent the first said uprights, said additional uprights extending only partially across the respective spaces, partitions constructed of fiber board, arranged in the spaces and secured to the said additional uprights, said partitions coöoperating with the inner walls of the refrigerator to form insulation spaces, insulating material in said insulation spaces, the spaces between the partitions and the respective adjacent outer walls forming dead air spaces, and a finishing coating of enamel on the exposed faces of the said inner walls.

3. A refrigerator having outer walls con-

structed of fiber board, corner uprights to which the walls are secured, inner walls 25 spaced from the outer walls, intermediate walls of fiber board arranged in the spaces between the said walls and being in turn spaced from both of the walls, means for maintaining the intermediate walls spaced 30 from the outer walls to form dead air spaces adjacent the outer walls, insulating material filling the spaces between the said intermediate and inner walls, and a binding element engaging over the adjacent edges of the 35 walls for securing said edges.

In testimony whereof we have signed our names to this specification, in the presence of two subscribing witnesses, on this 27th day of February, A. D. 1915.

LOUIS F. PERKETT.
EDWARD C. MADARY.
